UNITED STATES PATENT OFFICE

158,179

BAKING UNIT FOR FRANKFURTER
SANDWICHESFrederik Christie, Bronx, N. Y., assignor, by mesne assignments, to Irving Levine, New York, N. Y.

Application December 3, 1947, Serial No. 142,929

Term of patent 3½ years

(Cl. D81—10)

To all whom it may concern:

Be it known that I, Frederik Christie, a citizen of the United States of America, and resident of the Bronx, county of Bronx, and State of New York, have invented a new, original, and ornamental Design for Baking Unit for Frankfurter Sandwiches, of which the following is a specification, reference being had to the accompanying drawing, forming a part thereof, in which

Fig. 1 is a front perspective view of a baking unit for frankfurter sandwiches, embodying my new design, in closed position;

Fig. 2 is a view similar to Fig. 1, but with the dough receptacle swung to one side;

Fig. 3 is a view similar to Fig. 2, but with the mold cover in open position; and

Fig. 4 is a front perspective view of the baking unit for frankfurter sandwiches in closed position taken from the end opposite that shown in Fig. 1.

I claim:

The ornamental design for a baking unit for frankfurter sandwiches, substantially as shown and described.

FREDERIK CHRISTIE.
